E. LOEWENHERZ.
TOOTH CLEANING DEVICE.
APPLICATION FILED APR. 19, 1917.

Patented Jan. 18, 1921.

UNITED STATES PATENT OFFICE.

EMANUEL LOEWENHERZ, OF CHICAGO, ILLINOIS.

TOOTH-CLEANING DEVICE.

1,366,092.

Specification of Letters Patent. Patented Jan. 18, 1921.

Application filed April 19, 1917. Serial No. 163,276.

To all whom it may concern:

Be it known that I, EMANUEL LOEWENHERZ, a subject of the Emperor of Austria, residing at Chicago, in the county of Cook and State of Illinois, have invented a new and useful Tooth-Cleaning Device, of which the following is a specification.

The invention relates to improvements in tooth cleaning devices and especially to improvements in that class of devices in which a removable cleaning agent, like a pad, is inserted into a holder, and removed therefrom after its use.

An object of the invention is to provide in combination with a holder attached to a handle, a cleaner, preferably in the form of a pad inclosed in an envelop, this cleaner being secured in the device in such manner that its envelop or a portion of the envelop projecting from the holder may readily be removed.

Another object of the invention is to provide in combination with the holder, means for scoring, indenting or perforating the envelop along certain lines, whereafter portions of the envelop may readily be torn off.

Another object of the invention is to provide in combination with a cleaning pad, an envelop for the same, and means for inditing plainly those portions near the longitudinal central axis of the pad along which the pad is to be secured within the holder. By this means the user of the device will be assured that perforations provided in the envelop will come into engagement with additional devices for providing indentations or the like.

Another object of the invention is to provide a holder adapted to engage two outer surface portions of a cleaner, which has been folded by this engagement, and adapted to force certain portions of the cleaner toward other portions thereof, which are also engaged by a holding member, this second holding member being pivotally disposed with respect to that part of the device on which the outer holding elements are arranged.

The invention also provides means for relieving the pivot pin on which the second holding member is mounted of any excessive strain, and for this purpose the invention contemplates on the second holding member the provision of an extension adapted to receive that strain to which the said holding member is subjected when a cleaner in the

form of a pad or the like is inserted into the device.

Another object of the invention is to provide in connection with the support for the cleaner, a carriage having a relatively short sliding movement and adapted by this sliding movement to receive and lock or to unlock and release a cleaner.

Another object of the invention is to provide wedge portions on certain parts of the device adapted for co-action with other portions for the purpose of securely holding the carriage with the cleaner pad in locking position, said wedge portion being adapted to facilitate the complete release of the carriage and holding member, after the release has been initiated.

With these and other objects in view the invention is described in the following specification and the novel features thereof are more particularly pointed out in the claims appended thereto, reference being made in the specification to the accompanying drawing, wherein—

Fig. 1 is a top plan view of the device shown at a large scale.

Fig. 2 is a sectional view on line 2—2 of Fig. 1, showing the device in full lines in partly open position, and in dotted lines completely opened.

Fig. 3 is a similar section showing the device in closed position.

Fig. 4 is a section on line 4—4 of Fig. 3.

Fig. 5 is a section through the pivotal support of a holding member, on line 5—5 of Fig. 3.

Fig. 6 is a transverse section on line 6—6 of Fig. 3.

Fig. 7 is a section similar to the other transverse sections of Figs. 4, 5 and 6, showing a cleaner, in the form of a pad inclosed in an envelop, introduced into the device, and

Fig. 8 is a perspective view partly in section of a cleaning pad.

The device comprises a handle 1 which may be of oval or round cross section as indicated in Fig. 1 at 1, or which may consist of a flat bar as shown at 2 in Figs. 2 and 3. The front portion of this handle constitutes a support or head 3, which is flat and which is preferably somewhat narrower than the handle. This support may have approximately the length of an ordinary tooth brush, but it is much flatter and is provided on the longitudinal sides with marginal

guiding portions, consisting of grooves cut into the lower surface of the support, as shown at 4 and 5, and adapted to act as a means for guiding the carriage 6 in a rectilinear path.

The carriage constitutes a holding member for the cleaner and consists of a frame having side parts 8 and 9 which are shaped in cross section so as to embrace the guiding portions 4 and 5 of the support. Flanges 11' and 12' extend upwardly from the side parts 8 and 9 in spaced and parallel relation to each other, adapted to engage lateral surface portions of a cleaner 10. These 10 standing flanges may be provided with corrugations 13', or with pin points 14 near the upper end for purposes to be described below.

The front portions of the side parts 8 and 9 of the carriage 6 are united by a strap 11, which extends over the top surface of the support 3; the rear portions of the side parts are also united by a strap 12, the rear edge of which is united with the rear edge 25 of the side parts 8 and 9 by a low upright flange 13. This rear portion or strap 12 is provided near its center with a cut out 14' extending from the front edge of the strap inwardly and having a slightly beveled rear 30 edge 15, the cut out being capable of receiving and guiding a portion of a second or central holding member 23.

The rear portion of the support 3 is slightly offset, terminating in a short tongue 35 17 of substantially rectangular cross section, whereby a shoulder 18 is formed near the front end of this tongue. The rear strap 12 has its lower surface spaced a distance from the upper edge of the tongue 17, 40 this distance being approximately equal to the height of the shoulder. This space between the upper strap 12 and the extension or tongue is utilized for receiving the pivotal support as well as the rear end of the 45 second holding member when the entire device is in closed position.

The sliding motion of the carriage with respect to the support 3 of the device may be limited by pins 19 which extend from the 50 upper horizontal portion 25 to the lower horizontal portion 26 of the guiding flange 8 or 9 of the carriage, and which in the movement of the carriage slide from one end wall 20 of a cut out 21 in the guiding 55 margin of the support to the other end wall 22.

The second or companion holding member 23 is disposed in the device for coöperation with the first described holding member, the carriage. This second holding member 23 consists of a small beam, pivotally and slidably supported with respect to the head 3 and provided with upstanding holding flanges 24 which in the operative or 65 closing position of the device are in opposi-

tion to the flanges of the first described holding member. The upper edge of the flanges 24 on the second holding member may also be corrugated, or may be equipped with prick points to score and perforate the 70 material of the envelop for the cleaner. This second holding member is provided with transverse pivot pins 28 which are located in the space between the front portion of the upper strap 12 and the underlying 75 horizontal portions 26 of the flanges 8 and 9 which serve for guiding the carriage. It is to be noticed that there are no special pivot bearings for these pins 28 and that they are freely rotatable in the space described, requiring merely means for preventing sliding motion of these pins in forward or rearward direction with respect to the support of the second holding member. The sliding motion of these pivot pins in 80 rearward direction is prevented by the insertion of small bars 30 longitudinally into the interspace between the horizontal portions 25 and 26 of the guiding flanges of the carriage, and which may be held therein by 85 soldering, clamping or in some other suitable way.

The forward motion of the pivot pins 28 in the supporting element of the second holding member and with respect thereto is 90 prevented by a transverse pin 31 rigidly secured in the carriage and extending in front of the pivot pins 28 from one flange 8 of the carriage to the other flange 9.

It will be seen that by this means a forward or rearward displacement of the pivot pins 28 on which the central holding member 23 is adapted to swing in the carriage is prevented; that free oscillating movement of said holding member, however, is rendered possible, and that no special bearings are necessary for the pivot pins. Bearings of this character would have a tendency to increase the friction, and to make the device less compact than the construction described.

The bottom portion of the holding member 23 is provided on its under surface with corrugations or teeth 32, pins 33 or the like, to aid in preventing displacement of the 115 cleaner held by said members. The main portion of the beam 23 provided with upstanding flanges 24 is offset from the portion 34 on which the pivot pins 28 are mounted, this offset being due to a short angular intermediate portion 35 extending from the pivot pins 28 to the said flanged portion of the holding member.

This holding member furthermore is provided with a rearward extension or tail 125 piece 36 of sufficient width to swing between the two projecting elements which prevent rearward motion of the pivot pins 28. This rear extension 36 is of sufficient thickness to fit loosely into the interspace between the 130

flange portions 26 of the carriage and the lower surface of strap 12, or, when the carriage is in locked position to fit between the projecting tongue 17 on the support 3 and the lower surface of the strap 12.

The rear portion of this tail extension 36 is slightly thicker than the front portion of the same, so that by the motion of the carriage into locking position this thickened portion 37 of the tail extension 36 will come into clamping contact with the upper surface of the tongue 17 on the support 3, whereby the thickened portion acts as a wedge and locks the central holding member 23 in substantially horizontal position. In this position of said holding member the lower surface provided with pin points 33 or corrugations 32 is spaced from and parallel to the upper surface of the main part 20 of the support 3, Fig. 3.

At the front end of this holding member 23 is also provided a wedge shaped extension 37' adapted for entrance into a socket 38 provided in the adjacent portion 25 of the handle. The bottom surface of this socket is in a plane with the upper surface of the front strap 11 on which the forward portion of the holding member 23 normally rests.

Upon insertion of a cleaner, as, for instance, a compressible pad between the support 3 and the holding members 6 and 23, certain portions of this cleaner 10 are confined between the upstanding flanges 11', 35 12' and 24 of the holding members 6, 23 and the support 3. The strain which would be exerted thereby upon the pivots 28 and which has a tendency to force the holding member 23 upwardly, is absorbed by the tail extension 36 which is then wedged between the lower surface of the rear strap and the support 3, so that the pivot support of the holding member 23 is relieved of any strain. Upon insertion of a pad and 45 upon motion of the holding member 23 into locking position, the elasticity of the cleaner portion held between the several flanges will also have a tendency to force the entire holding member 23 upwardly 50 away from the support 3 and the extension or tongue 37' of the holder will be pressed against the top wall of the socket 38 into which the tongue has been inserted. This pressure will also have locking effect upon 55 the holding member 23.

The wedge action of the tail extension 36 on the pivotal holding member 23 with respect to the rear strap 12 of the carriage will not have only the effect of pressing the said holding member 23 downwardly into engagement with the central portion of the cleaner 10, but it will also have a tendency of locking the other holding member, namely, the carriage 6 against longitudinal displacement on the support 3, avoid-

ing thereby the accidental shifting of the holding member 6 when the cleaning device is in use.

In order to maintain the cleaner, preferably in the form of a pad 10 in proper position and to facilitate the localizing of the same, the pad and preferably also the envelop 41 for the same are provided with suitable notches 42 at opposite ends of the longitudinal axis of the pad, these notches 75 being placed underneath the beam 23 when the pad is inserted in the device. The pad 10 is advisably made of absorbent material and may be impregnated or saturated with a suitable mouthwash, paste or the like before the envelop is applied; the envelop will then serve for maintaining the cleaner in sanitary aseptic condition until it is used, and will prevent contamination of the material while it is being inserted in the 80 device. The envelop 41 of the pad is provided with perforations 42' on opposite surfaces and at equal distances from the central axis, the distance of these lines of perforations or scorings having been selected 85 so that these perforations will come into opposition with the pricks or corrugations on the flanges of the holding member 6, 23. These perforations of the envelop therefore constitute means for facilitating the removal of the envelop on a predetermined line and additional means are formed on the holders for facilitating this removal.

I claim:

1. A tooth cleaning device, comprising in combination a stationary support, a holding member movable thereon, a companion holding member movable with respect to said first named holding member and to the support, means on said support and on the first named holding member for locking the second holding member in operative position.

2. A tooth cleaning device, comprising in combination a stationary support, a holding member slidable thereon, a companion holding member slidable with respect to said support and oscillatable with respect to said first named holding member, means on said support and on the first named holding member for locking the second holding member in operative position.

3. A tooth cleaning device, comprising in combination a stationary support, a holding member movable thereon, a companion holding member movable with respect to said first named holding member and to the support, and locking means for said second holding member, said locking means being disposed on said support and the first named holding member and being adapted to secure said second holding member in operative position upon movement of said second holding member with respect to said first holding member and upon movement of

both of said holding members in a predetermined direction with respect to said support.

4. A tooth cleaning device, comprising in combination a stationary support, a holding member movable thereon, a companion holding member movable with respect to said first named holding member and to the support, means on said support and the first named holding member for locking said second holding member in operative position and means on said second holding member for holding the first named holding member in operative position with respect to said support.

5. A tooth cleaning device, comprising in combination a stationary support, a holding member thereon, a second holding member slideable and oscillatable with respect to said support, means on said support and the first holding member for locking the second holding member in operative position upon movement of said holding member with respect to said support in predetermined direction.

6. A tooth cleaning device, comprising in combination a stationary support, a holding member thereon, a second holding member slideable and oscillatable with respect to said support, means on said support and first holding member for locking the second holding member in operative position, and means on said second holding member for holding the first named holding member in operative position with respect to said support.

7. A tooth cleaning device, comprising in combination a stationary support, a holding member thereon, a companion holding member pivoted between its ends to said first named holding member, means on the support for locking one end of said second holding member in operative position upon sliding movement of said second holding member, and means on the first holding member coöperating with the support for holding the other end of the second holding member in operative position upon oscillatory and sliding movement of said second holding member with respect to said support.

8. A tooth cleaning device, comprising a

stationary support, a holding member movable thereon, a second holding member movable with respect to said first named holding member and the support, means on the support for limiting the movements of said holding members, means operative upon sliding movement of said first named holding member in a predetermined direction with respect to the support for locking the first named holding member in operative position with respect to the support, and means for holding the second named holding member in operative relation with respect to said first named holding member and to said support.

9. A tooth cleaning device, comprising in combination a support, a holding member, a second holding member adapted for co-operation with the first named holding member, said second holding member being slideable and oscillatable with respect to said support and being provided with an extension, and said support being provided with a socket adapted to receive said extension for locking said second holding member, after pivotal and sliding movement in a predetermined direction, in operative position with respect to said support.

10. A tooth cleaning device, comprising a support, a carriage slideable on the support, a holding beam pivoted on the slideable carriage, the support having a socket for receiving one end of the holding beam, means movable with the carriage for preventing displacement of the pivot of the beam on the carriage, and means on said beam for holding the carriage in locked relation with respect to the support.

11. A tooth cleaning device, comprising a stationary support, a carriage slideable thereon, a longitudinal holding beam pivoted to said carriage, the support having a socket for receiving one end of said holding beam, a wedge extension on the holding beam, a tongue on the support, and a strap on said carriage adapted for coöperation with the wedge extension to force said extension into locking engagement with the tongue of the support.

Chicago, Illinois, April 16th, 1917.

EMANUEL LOEWENHERZ.
